APPARATUS FOR COATING METAL SHEETS

John E. Elswick, Steubenville, Ohio

Application February 24, 1938, Serial No. 192,267

6 Claims. (Cl. 91—12.5)

This invention relates to apparatus for coating metal sheets and more particularly to apparatus for coating ferrous sheets with tin to form what is known as tinplate.

5 In the production of tinplate, the base sheets are first pickled and then dipped into pure molten tin. The tin forms an alloy with the surface of the ferrous sheet to which a layer of tin adheres. To insure a good bond between the base sheet and the tin, it is necessary that the sheets be fluxed. This is accomplished by the use of a flux consisting usually of a mixture of zinc and ammonium chlorides, which is floated on a portion of the surface of the molten tin and is kept in a fused state by the heat of the molten tin.

In the coating operation the sheets are passed into the tin pot by hand or machine and are carried by suitable mechanical means through the flux and the molten tin and out through a layer of palm oil which covers another portion of the surface of the molten tin.

The flux has a tendency to oxidize and form a hard surface which causes foreign particles to adhere to the sheets as they are passed through the flux. The adherence of these foreign particles to the sheets causes a defective tin coating and the sheets must be scrapped or sold as "seconds". Formation of this hard surface may be prevented by continuous agitation of the surface of the flux. It is the purpose of my invention to provide apparatus for tinning metal sheets in which the surface of the flux is continuously agitated and defects in the coating of the sheets are prevented.

35 In the accompanying drawings I have illustrated a present preferred embodiment of my invention in which

Figure 1 is a transverse vertical section of the assembled apparatus along the lines I—I of Figure 2,

40 Figure 2 is a longitudinal section of the assembled apparatus along the lines II—II of Figure 1,

Figure 3 is a longitudinal section of a holder used in my apparatus,

45 Figure 4 is a transverse section along the lines IV—IV of Figure 3,

Figure 5 is an elevation view of the follower contained within the guide shown in Figures 3 and 4, and

50 Figure 6 is a plan view of the follower shown in Figure 5.

Figures 1 and 2 show the arrangement of my entire apparatus. A tin pot 7 which holds the molten tin is divided by a partition 8 into an

entering chamber 9 and a discharge chamber 10. A passageway 11 in the partition 8 connects the chambers 9 and 10. The height of the molten tin is indicated by the dot-and-dash line 12 and the height of the flux is indicated by the dot-and-dash line 13.

The mechanism for feeding the base sheets through the flux and molten tin comprises three pairs of feed rolls 14, 15 and 16 mounted between two housings 17 and 18. A strut 19 secured to the housings 17 and 18 by angles 20 braces the housings at their lower ends and carries a block 21 which provides additional support to the lower feed rolls 16.

Guides 22 and 23 insure that the sheets in passing from the feed rollers 15 will enter the nip of the feed rollers 16. The guide 23 extends between the housings 17 and 18 and serves as additional bracing. The guide 22 is pivoted about the bolt 24 and may be adjusted by means of the bolt 25 which moves in the slot 26.

The bottom roll of the feed rolls 16 is driven from a suitable source of power through miter gears 27 and is geared to the upper roll of the feed rolls 16 by the pinions 28. The upper feed rolls 14 are connected to a suitable source of power by the chain 29 and sprocket wheel 30.

A chain hook 31 is provided by means of which the entire apparatus may be lifted out of the tin pot 7 when desired. A chain hook 32 detachably connected to the partition 8 by a yoke 33 and a set screw 34 is provided for moving the pot by means of a crane.

55 A dot-and-dash line 36 indicates the path of the base sheets through the flux and molten tin. The flux is agitated by a rake 35 which extends down into the slag to the surface of the molten tin. This rake is moved back and forth across the surface of the slag adjacent to the plane of the base sheets by mechanism which will now be described. Brackets 37 bolted to the sides of the tin pot support sleeve bearings 38. Brackets 39 extend from the brackets 37 at right angles thereto and support a bar 40 which braces the ends of the brackets 37. A right-and-left hand threaded shaft 41 is mounted on the bearings 38 and is turned by a chain 42 which passes over a sprocket wheel 43 secured to the shaft 41 and a sprocket wheel 44 mounted on the same shaft as the sprocket wheel 30, which drives the entering feed rolls 14. The rake 35 is carried by a holder designated generally by the reference numeral 45 which moves back and forth along the threaded portion of the shaft 41.

Figures 3 and 4 illustrate the mechanism by

which the holder 45 is caused to move back and forth along the shaft 41. Two bushings 46 fit about the shaft 41 and carry a casing 47. A retainer 48 is bolted to the casing 47 and forms 5 with the casing a cylindrical space 49 in which a cylindrical follower block 50 may turn about its vertical axis. The follower block 50 carries a follower 51 which is designed to slide in the threads 52 of the shaft 41. The follower 51 is 10 fitted into a groove 53 in the follower block and is held by a pin 54. As shown in Figures 5 and 6 the follower 51 is cut to fit one-half of the threads cut in the shaft 41 and is bevelled at the ends to insure free motion therein.

15 As the shaft 41 revolves, the follower 51 will slide in the threads 52 of the shaft and thereby be forced along the shaft 41. As the follower moves along the shaft 41 it will carry with it the follower block 50 and consequently the entire 20 holder 45. When the holder 45 reaches either end of the threaded portion of the shaft 41, continued revolution of the shaft will cause the follower block 50 and follower 51 to rotate about a vertical axis and engage the set of threads 25 which is cut in the opposite direction from the set with which the follower had previously been engaged. The oppositely cut threads will then cause the follower 51 and thereby the holder 45 to move across the tin pot 7 in an opposite direction.

The rake 35 slides into a sleeve 55 and is retained in position therein by a set screw 56. The depth to which the rake extends into the flux 35 may thereby be easily adjusted. A tongue 57 is welded to the top of the sleeve 55 and fits into a groove 58 cut in the retainer 48. It is held in the groove by the pin 59.

The rake is thus caused to reciprocate across the surface of the flux adjacent to the plane 40 in which the base sheets enter the flux. The continuous agitation of the flux prevents the formation of a hard surface of oxidized flux which would cause foreign particles to adhere to the sheets and produce sheets with defective 45 coatings.

While I have described a present preferred embodiment of my invention, it is to be understood that it may be otherwise embodied within the scope of the following claims:

1. Apparatus for coating metal sheets with tin comprising a pot adapted to hold a bath of molten tin with a layer of flux thereon, means 5 for feeding the metal sheets to be tinned through said bath, stirring means extending into said flux, a right-and-left hand threaded shaft for driving said stirring means across the pot, and a holder supporting said stirring means and having a follower cooperating with the threads of said shaft.

10 2. Apparatus for coating metal sheets with tin comprising a pot adapted to hold a bath of molten tin with a layer of flux thereon, means for feeding the metal sheets to be tinned through said bath, stirring means extending into said 15 flux and means for imparting to said stirring means a reciprocating motion across the pot.

20 3. An agitator for stirring flux in a tinning pot comprising stirring means extending into the flux, a threaded shaft for imparting to the stirring means a reciprocating motion along the surface of the flux, a holder cooperating with said shaft and supporting said stirring means, and driving means for revolving the shaft.

25 4. An agitator for stirring flux in a tinning pot comprising stirring means extending into the flux, a right-and-left hand threaded shaft for imparting to the stirring means a reciprocating motion along the surface of the flux, a holder supporting said stirring means and having a 30 follower cooperating with the threads of said shaft, and driving means for uni-directionally revolving the shaft.

35 5. An agitator for stirring flux in a tinning pot comprising stirring means extending into the flux, a shaft having threads cut therein for imparting to the stirring means a reciprocating motion along the surface of the flux, a guide cooperating with said shaft and supporting said stirring means, a follower turning in said guide 40 and sliding in the threads of the threaded shaft, and driving means for revolving the shaft.

40 6. Apparatus for stirring flux in a tinning pot comprising a shaft extending across the tin pot, stirring means mounted for movement longitudinally of the shaft, and means effective upon uni-directional rotation of the shaft for reciprocating the stirring means.

JOHN E. ELSWICK.
